DESIGN FOR A JEWELRY FINDING

Michael Chernow, New York, N. Y.

Application July 19, 1947, Serial No. 140,405

Term of patent 7 years

(Cl. D45—1)

To all whom it may concern:

Be it known that I, Michael Chernow, a citizen of the United States and residing at New York, in the county of New York and State of New York, have invented a new, original, and ornamental Design for Jewelry Finding, of which the following is a specification, reference being had to the accompanying drawings, forming part thereof, and in which

Fig. 1 is a top plan view of a jewelry finding, showing my new design;

Fig. 2 is a side elevational view thereof;

Fig. 3 is an end elevational view from one end thereof; and

Fig. 4 is an end elevational view from the opposite end thereof.

I claim:

The ornamental design for a jewelry finding, substantially as shown.

MICHAEL CHERNOW.
